UNITED STATES PATENT OFFICE.

STEPHEN I. FEKETE, OF DETROIT, MICHIGAN, ASSIGNOR TO HUDSON MOTOR CAR COMPANY, OF DETROIT, MICHIGAN, A CORPORATION OF MICHIGAN.

LATCH SPINDLE AND LOCK ASSEMBLY.

Application filed January 26, 1926. Serial No. 83,963.

This invention relates especially, although not exclusively, to combined latches and locks for the doors of closed automobile bodies.

5 It is customary to provide the door of an automobile body with a latch which is usually secured to the inner side of the door and is operated by a latch spindle which extends through the door and is provided 10 at the outer side of the latter with an operating handle. It is also customary, in the case of doors of closed automobile bodies, to provide at least one door with a key-operated lock accessible at the exterior of the door 15 and operable to lock the latch against operation by the outside handle. This lock, while located at the exterior of the door, is usually arranged to cooperate with the latch mechanism at the inner side thereof, 20 so that some form of connection extending through the door must be provided. Such an arrangement includes a relatively large number of parts which are difficult to assemble and to hold in their proper relative positions, and objectionable cramping of the working parts frequently results. This is particularly troublesome in the case of metal doors of the character now largely used, in which fitting of the various parts in 25 place, or during assembly, is very difficult.

30 The present invention has for its object to provide a simple sub-assembly, including an escutcheon plate, a latch spindle, and a lock, which may be applied as a unit to the outside of the door and cooperate with the latch mechanism on the inside of the door, the latch spindle being so mounted in the plate as readily to compensate for variations in the relative positions of the parts, and 35 the lock cooperating with the spindle to lock the latter against latch releasing movement irrespective of the variable position of said spindle.

40 The foregoing and other objects of the invention, together with means whereby the latter may be carried into effect, will best be understood from the following description of a preferred form or embodiment thereof illustrated in the accompanying drawings. It will be understood, however, 45 that the particular construction described and shown has been chosen for purposes of exemplification merely, and that the invention, as defined by the claims hereunto ap-

pended, may be otherwise embodied without 55 departure from the spirit and scope thereof.

In said drawings:

Fig. 1 is a vertical sectional view of an assembly embodying the invention, showing the same in position in an automobile door, 60 the latter being shown in broken lines.

Fig. 2 is a front elevation of the assembly, showing the parts in locked position.

Fig. 3 is a similar view showing the latch spindle unlocked and turned into latch releasing position.

Referring to Fig. 1, a portion of an automobile door is shown in broken lines at 10, said door having secured to the inner side thereof a suitable latch generally indicated 70 at 11. Said latch is operated by a spindle 12 extending through the door 10 and provided at its outer end with a suitable operating handle 13. The latch spindle 12 is carried by and mounted to turn in an escutcheon plate 14, preferably provided with openings 15 (Figs. 2 and 3) to receive screws or other fasteners 16, whereby the same may be secured to the outer face of the door 10. As shown in Fig. 1, the escutcheon plate 14 is 80 formed in two parts 14^a and 14^b secured together by rivets or other fasteners 17 and having registering openings 18 through which the spindle 12 passes, said openings being of a suitable size to provide a limited 85 clearance about said spindle. The hub 19 of the handle 13 and the outer section 14^a of the escutcheon plate 14 are formed to constitute the elements of a ball and socket joint or connection as indicated at 20, said 90 ball and socket connection permitting a substantially universal movement of the spindle 12 in the escutcheon plate to an extent limited by the clearance afforded by the openings 18. The position of the axis of the 95 spindle in the plate may, therefore, be varied to compensate for any errors in the relative positions of the parts and to permit said spindle to cooperate properly with the latch 11.

100 The sections 14^a and 14^b of the escutcheon plate 14 are formed, at one side of the latch spindle 12, with oppositely offset portions 21 between which is secured a cylinder lock 22 of any suitable construction adapted to 105 be operated from the outer side of the door by a key 23. The cylinder of the lock 22 is provided with an eccentric preferably

semi-cylindrical projection 24 adapted, when said cylinder is in locking position, as shown in Figs. 1 and 2, to cooperate with and be directly engaged by a radially extending finger 25 carried by the spindle 12, thereby locking the spindle against latch-releasing turning movement. When the lock is turned into the position shown in Fig. 3, the projection 24 is moved out of the path of movement of the finger 25, thereby permitting the handle 13 and spindle 12 to be turned into the position shown in said figure to release the latch.

The elements of the ball and socket connection 20 are held in close engagement with one another, so as to prevent rattling, by a spiral spring 26 surrounding the spindle 12 and bearing at its opposite ends respectively against the hub of the finger 25 and a thimble 27 loosely mounted on the spindle and engaging the inner face of the inner section 14° of the escutcheon plate.

It will be observed that the means for locking the outside latch operating handle 25 are extremely simple and comprise directly interengaging parts on the spindle and lock. It will also be noted that the arrangement of these parts is such as to provide for their locking interengagement irrespective of the movement of the spindle permitted by the ball and socket connection, being such as to cause locking of the spindle in any position of the axis of the latter permitted by the clearance of the openings 18.

35 The escutcheon plate, latch spindle, and lock may be assembled with one another at

the bench and tested for working fits and may, thereafter, be applied as a unit to the door, the necessary compensation for variations in different doors being taken care of by the universal movement of the spindle in the escutcheon plate, and the operative relationship of the parts being unaffected by this single variation. The construction of the parts is materially simplified and cheapened, the final assembly materially facilitated, and all danger of cramping positively prevented.

Having thus described my invention, I claim:

1. A latch spindle and lock assembly comprising an escutcheon plate, a latch spindle mounted to turn therein and having a radially extending finger, and a cylinder lock carried by said plate at one side of said spindle, said cylinder having an extending portion adapted to be moved into or out of the path of movement of said finger to lock or unlock said latch spindle by turning the cylinder.

2. A latch spindle and lock assembly comprising an escutcheon plate composed of two parts permanently secured together, a latch spindle mounted in said plate provided with a radially extending finger, and a cylinder lock held between the parts of said plate, said cylinder having an extending portion adapted to be moved into or out of the path of movement of said finger to lock or unlock said latch spindle by turning the cylinder.

In testimony whereof I affix my signature,
STEPHEN I. FEKETE.
